DESIGN FOR A COMBINATION BOTTLE AND CAP

Samuel Rubin, New York, N. Y.

Application October 17, 1938, Serial No. 80,483

Term of patent 14 years

To all whom it may concern:

Be it known that I, Samuel Rubin, a citizen of the United States and a resident of the city of New York, in the county of Kings and State of New York, have invented a new, original, and ornamental Design for a Combination Bottle and Cap, of which the following is a specification, reference being had to the accompanying drawing, constituting a part thereof.

The figure is a perspective view of a combination bottle and cap showing my new design.

The characteristic features of my design reside in the cylindrical cap in combination with the cylindrical bottle, the cap being of substantially the same diameter as the bottle and in height proportioned to the bottle substantially as shown.

I claim:

The ornamental design for a combination bottle and cap, substantially as shown and described.

SAMUEL RUBIN.
